UNITED STATES PATENT OFFICE.

ALBERT WEINRAUB, OF NEW BRUNSWICK, NEW JERSEY.

DESIGN FOR A FAN FOR SEWING-MACHINES.

SPECIFICATION forming part of Design No. 31,405, dated August 15, 1899.

Application filed July 25, 1899. Serial No. 725,114. Term of patent 3½ years.

To all whom it may concern:

Be it known that I, ALBERT WEINRAUB, a citizen of the United States, residing at New Brunswick, in the county of Middlesex and State of New Jersey, have invented and produced a new and original Design for a Fan for Sewing-Machines, of which the following is a specification.

The invention relates to a new and original design for a fan for sewing-machines; and it has for its object to provide a design of this character which will be both useful and ornamental.

The essential feature of the design resides in a circular flange having a flat central circular portion and provided with radial blades set at an angle and having their inner ends merging into the central circular portion, said wheel having an annular series of parallel connecting-pieces arranged approximately at right angles to the outer edges of the blades.

In the drawings, Figure 1 is a perspective view of a fan, showing my new and original design. Fig. 2 is an elevation of the same.

Referring to the drawings, 1 designates a

circular fan provided with a central circular portion 2 and having radial blades 3 extending from the central circular portion and arranged at an angle. The inner portions or ends of the radial blades merge into the central circular portion, and the bends 4 form approximately triangular extensions of the central circular portion and produce a central star-shaped figure. The central circular portion 2 is provided with oppositely-disposed hub extensions 5, which are cylindrical. The wheel is provided at its periphery with an annular series of parallel connecting-pieces 6, arranged approximately at right angles to the end edges of the blades.

What is claimed is—

The design for a fan, herein shown and described.

In testimony that I claim the foregoing as my own I have hereto affixed my signature in the presence of two witnesses.

ALBERT WEINRAUB.
